(57) **CLAIM**

The ornamental design for an infrared sensor, substantially as shown and described.

DESCRIPTION

FIG. 1 is a perspective view of an infrared sensor. FIG. 2 is another perspective view of the infrared sensor of FIG. 1. FIG. 3 is a front view of the infrared sensor of FIG. 1. FIG. 4 is a back view of the infrared sensor of FIG. 1. FIG. 5 is a left view of the infrared sensor of FIG. 1. FIG. 6 is a right view of the infrared sensor of FIG. 1. FIG. 7 is a top view of the infrared sensor of FIG. 1; and, FIG. 8 is a bottom view of the infrared sensor of FIG. 1. The broken lines which define the bounds of the claimed design form no part thereof.
